UNITED STATES PATENT OFFICE.

WALTER C. LINDEMANN AND ADOLPH W. BENSON, OF MILWAUKEE, WISCONSIN, AS-
SIGNORS TO A. J. LINDEMANN & HOVERSON COMPANY, OF MILWAUKEE, WISCON-
SIN, A CORPORATION OF WISCONSIN.

FOLDING PORTABLE-STOVE FRAME.

Application filed August 23, 1927. Serial No. 214,804.

The improvements relate to portable stoves and to stoves of this character which are to be folded or knocked down for packing, carrying or other transportation and may be 5 opened up and placed in position by unskilled persons, and without the employment of tools of any description or the necessity for making or breaking permanent connections. The stove is intended to be used with gasoline or 10 other vapor burners, but certain features of the improvements may be employed with burners of other character. The stove provided by the improvements may also be used permanently if desired, or in summer camps 15 or cottages, as well as for camp cooking and similar uses.

The principal objects of the improvements are to provide a portable or "camp" stove which is simple, strong and efficient, answers 20 all the ordinary purposes of outdoor or other light cooking and can be opened up and placed in condition for use or folded and put in condition for carrying by any person of ordinary intelligence and without danger that any of 25 the parts will be improperly positioned or adjusted, and will in use provide safe, convenient and efficient means for all ordinary cooking operations.

The improvements are illustrated in the accompanying drawings, in which

Fig. 1 is a front perspective view of a portable vapor stove in position for use, with the top grid or grate turned up instead of being down in horizontal position for the support 35 of cooking utensils or appliances;

Fig. 2 is a similar view of the stove folded for transportation and with the body inverted from the position of Fig. 1, one part of bottom, which in use forms one of the legs, being 40 raised; and

Fig. 3 is a view similar to Fig. 1 of the stove in position for use supported on its folding legs, but with the top cover enclosing the burners and burner parts closed down, showing 45 the manner in which the stove may be kept when not actually in use, but ready for use.

Referring to the drawings, the body or fixed housing frame 1 consists of a rectangular frame of sheet metal having openings 2, 3 and 50 4 through which the valve stems of the burners may be operated by means of a key 6 or other suitable instrument, this key being connected with the inner frame of the burners

and their connections by means of a chain 7 so that it cannot be lost. An ordinary pair 55 of pincers or pliers, however, can be employed to engage the square ends of the burner valve stems 9, 10 and 11 if desired. On the front or top member of the body 1 is a handle 12 consisting of a substantially U-shaped bar 60 having its ends rotatably held in sleeves 13 secured to the said member, while below the handle attachment in the same member are holes 14 to receive the inwardly turned ends 65 of the rods 15 which secure and hold the legs 16 in position while supporting the stove.

The construction and arrangement of these diagonal rods 15 is peculiar, and this construction and arrangement and that of the legs 16, in connection with the relations between these parts is one of the features of the improvements which render the stove simple, strong and convenient. The rods 15 have corresponding rods 15' at the back of the stove which engage the back, bottom member of 75 the body in the same manner as that in which the rods 15 engage the front members, and the two rods are connected by a horizontal section 15" extending through the sleeves 17 secured inside of the legs 16. The two rods 80 and connecting portion are made all in one continuous piece of heavy wire or rod steel, and are held against movement bodily by vertical flanges 16' of the legs. Normally the connecting rods are within the plane of 85 the legs, and therefore in order to make them engage the holes 14 in the body they must be flexed outwardly to a slight extent and moved upwardly until their inturned ends register with the holes 14, when they may be released 90 and the said ends permitted to snap into the holes to make a secure connection and one which will hold against all ordinary stresses to which they may be subjected in use. When disconnected from the body they fall to the 95 position shown in dotted lines in Fig. 3 and are folded in with the legs against the body, being housed within the flanges 16'.

The legs are connected with the ends of the body by means of hinges 18 at the lower 100 edges of said ends. When the legs are folded down against the body of the stove (see Fig. 2) their vertical flanges fit inside the lower edge of the said body, and the two legs— 105 which now form one side of the enclosing box—are secured together in closed position

by means of the wedge shaped loop 20 of the strap 19 secured to the outside of one of the legs, which is engaged by the latch 21, rotatably secured on the other leg, when it is 5 swung around so that its outer end enters the loop and is pressed into the same so that it will be wedged between it and the leg to form a secure connection. The outer inwardly turned ends 22 of the strap 19 overlap the 10 edges of the body at front and back and support the legs securely in closed position.

The top cover or opposite side of the enclosing box or housing of the stove, 23, is hinged to the top edge of the back at 24, and 15 when closed is secured by the swinging latch hook 25 on the front, which engages the projecting loop 26 secured to the front edge of the said member 23. When the stove is opened for use this lid or cover 23 is swung 20 backwardly on its hinges 24 to substantially horizontal position and is supported in this position, in which it forms a shelf or tray by the legs 27 rotatably connected to the side edges thereof and held in a sleeve 28 formed 25 by curling over the said side edges of the cover. The outer edge of the cover is turned at substantially right angles thereto to form a flange 29 which houses the legs 27 when they are turned to a position at right 30 angles to their open supporting position, and also overlaps the front of the body to make a comparatively tight closure when the cover is closed down.

Within the edges of the cover 23 is a shield 35 pivoted thereto by means of the pintles 30 removably connected to the back member of the shield at its ends by running through the sleeves 40 thereof and held in the sleeve 31 secured to the inner side of the cover 23 at the 40 rear of its side edges. The side members 32 of the shield are hinged at their back edges to the ends of the rear members 33, as shown at 34, 34' where the pintles 30 extend through their sleeves, and extend forwardly to a point 45 beyond the burners to protect the burners and the articles over them and on the shelf formed by 23. When the stove frame is folded the side members 32 are first folded back against the back member 33 and the back member 50 then turned down in the inside of the cover 23, so that these parts lie flat against the inner side of said cover. It will be seen that the legs 27 are housed between the rear edge of the shield and the flange 29, when not in use. 55 The grid or grate 41 consists of a continuous spring rod or wire bent to form an open grid and having its ends turned and held in the sleeves 35 at the back of the burner supporting frame 36. In this manner it is constructed and arranged to be swung to vertical position and down to horizontal position over the burners, and may be removed if desired by simply flexing its ends and withdrawing them from their sleeves. When it 60 is desired to move the stove, without folding

it, this grid may be turned up to vertical position and the entire stove lifted and carried by using it as a handle.

The construction and arrangement of the burners and tank and the frame for supporting them are not a part of the present improvements, and are described and claimed in a copending application by Walter C. Lindemann, one of the joint inventors hereof—The frame, however, consists of members arranged 75 in a rectangle and secured inside the body of the stove, and a tank 37 with burner supply pipe 38 and burners 39 are supported thereon.

We claim:

1. In a device of the character described, 80 the combination of a hollow angular body frame open at top and bottom and having vertical sides and ends, sheet metal legs hinged to the lower part thereof at the ends and constructed and arranged to swing inwardly against the body frame to form a bottom closure and outwardly to form supporting legs for said body, burners housed in said body, a cover member hingedly connected with one upper edge of the body and 85 adapted to be swung outwardly to horizontal position to form a supporting shelf or table and inwardly to close the said body portion, leg braces between the leg and body members pivotally connected with one of said members to swing to position between the two members and normally within their edges and capable of being flexed laterally beyond the 90 said members and to spring into an aperture in the other member to form a rigid connection 95 between the said two members.

2. In a device of the character described, 100 the combination of a hollow angular body frame open at top and bottom and having vertical sides and ends, sheet metal legs hinged to the lower part thereof at the ends 105 and constructed and arranged to swing inwardly against the body frame to form a bottom closure and outwardly to form supporting legs for said body, burners housed in said body, a cover member hingedly connected with one upper edge of the body and adapted to be 110 swung outwardly to horizontal position to form a supporting shelf or table and inwardly to close the said body portion, leg braces between the leg and body members pivotally connected with one of said members to swing to position between the two members and normally within their edges and capable of being 115 flexed laterally beyond the said members and to spring into an aperture in the other member to form a rigid connection between the said two members, said bracing members comprising a piece of attenuated spring metal 120 extending through said pivotal connection and turned away from the same at front and back of said members with which they coact to form a diagonal strut or brace between them.

3. In a device of the character described, the 130

- combination of a hollow angular body frame open at top and bottom and having vertical sides and ends, sheet metal legs hinged to the lower part thereof at the ends and constructed and arranged to swing inwardly against the body frame to form a bottom closure and outwardly to form supporting legs for said body, burners housed in said body, a cover member hingedly connected with one upper edge of the body and adapted to be swung outwardly to horizontal position to form a supporting shelf or table and inwardly to close the said body portion, leg members for said table pivotally connected therewith and constructed and arranged to be turned to positions lying on said table and extending downwardly to support the same, and foldable inwardly with said table when in the first position.
4. In a device of the character described, the combination of a hollow angular body frame open at top and bottom and having vertical sides and ends, sheet metal legs hinged to the lower part thereof at the ends and constructed and arranged to swing inwardly against the body frame to form a bottom closure and outwardly to form supporting legs for said body, burners housed in said body, a cover member hingedly connected with one upper edge of the body and adapted to be swung outwardly to horizontal position to form a supporting shelf or table and inwardly to close the said body portion, sleeves on the side edges of said table member, and legs hingedly connected therewith consisting of angular metal bars each having one leg extending through said sleeve and rotatable therein and the other extending at an angle therefrom to form a leg support when downwardly turned.
- 40 5. In a device of the character described, the combination of a hollow angular body frame open at top and bottom and having vertical sides and ends, sheet metal legs hinged to the lower part thereof at the ends and constructed and arranged to swing inwardly against the body frame to form a bottom closure and outwardly to form supporting legs for said body, burners housed in said body, a cover member hingedly connected with one upper edge of the body and adapted to be swung outwardly to horizontal position to form a supporting shelf or table and inwardly to close the said body portion, leg members for said table pivotally connected therewith and constructed and arranged to be turned to positions lying on said table and extending downwardly to support the same, and foldable inwardly with said table when in the first position, a flange extending along the outer edge of said shelf member, said leg adapted to be folded inside said flange.
6. In a device of the character described, the combination of a hollow angular body frame open at top and bottom and having vertical sides and ends, sheet metal legs hinged to the lower part thereof at the ends and constructed and arranged to swing inwardly against the body frame to form a bottom closure and outwardly to form supporting legs for said body, burners housed in said body, a cover member hingedly connected with one upper edge of the body and adapted to be swung outwardly to horizontal position to form a supporting shelf or table and inwardly to close the said body portion, a vertical folding shield on said table member extending along the outer edge thereof and along the side edges thereof and over the body frame, said shield having its side portions foldable in horizontal plane on the rear portion and the said rear portion foldable therewith in vertical plane against the upper and
- 70 75 80 85 90 95 100 105 110 115 120 125 130

inner surface of the table, the said connection comprising a sleeve member secured to the table, sleeves formed on both side and rear portions of the shield at their rear and side edges respectively and a pintle having an angular portion in said first-named sleeve and an upwardly extending portion extending through the said sleeve members of the shield portions.

9. In a device of the character described, 10 the combination of a hollow angular body frame open at top and bottom and having vertical sides and ends, sheet metal legs hinged to the lower part thereof at the ends and constructed and arranged to swing inwardly 15 against the body frame to form a bottom closure and outwardly to form supporting legs for said body, burners housed in said body, a cover member hingedly connected with one upper edge of the body and adapted 20 to be swung outwardly to horizontal position to form a supporting shelf or table and inwardly to close the said body portion, and a piece of attenuated spring metal bent to form 25 an open grate hinged to one edge of the body portion and pivotal to vertical position and horizontal position over the said burners, said hinged connection between the grid and the body comprising horizontally turned ends of the grid and sleeves fixed to the body frame 30 to receive them.

10. In a device of the character described, the combination of a hollow angular body frame open at top and bottom and having vertical sides and ends, sheet metal legs hinged to the lower part thereof at the ends and constructed and arranged to swing inwardly against the body frame to form a bottom closure and outwardly to form supporting legs for said body, burners housed in said body, a cover member hingedly connected with one upper edge of the body and adapted to be swung outwardly to horizontal position to form a supporting shelf or table and inwardly to close the said body portion, and a piece of attenuated spring metal bent to form 35 an open grate hinged to one edge of the body portion and pivotal to vertical position and horizontal position over the said burners, said hinged connection between the grid and the body comprising horizontally turned ends of the grid and sleeves fixed to the body frame to receive them, the resilience of the spring metal of the grid being such that it may be flexed to remove said ends from their sleeves, but tending to hold 40 them therein against normal stresses, including the stresses caused by using the grid as a handle to lift the stove means for connecting said legs in closed position and securing the cover formed thereby comprising a strap extending across one leg, said strap extending beyond the edges of the leg overlapping the edges of the body frame and having angular flanges engaging the exterior of said body frame.

- 50 45 55 60 65 70 75 80 85 90 95 100 105 110 115 120 125 130
11. In a device of the character described, the combination of a hollow angular body frame open at top and bottom and having vertical sides and ends, sheet metal legs hinged to the lower part thereof at the ends and constructed and arranged to swing inwardly against the body frame to form a bottom closure and outwardly to form supporting legs

for said body, burners housed in said body, a cover member hingedly connected with one upper edge of the body and adapted to be swung outwardly to horizontal position to form a supporting shelf or table and inwardly to close the said body portion, and means for connecting said legs in closed position and securing the cover formed thereby comprising a strap extending across one leg intermediate its ends and having a loop therein forming a tapered aperture between it and the leg, and a movable latch device on the other leg constructed and arranged to be pressed into said loop.

12. In a device of the character described, 80 the combination of a hollow angular body frame open at top and bottom and having vertical sides and ends, sheet metal legs hinged to the lower part thereof at the ends and constructed and arranged to swing inwardly against the body frame to form a bottom closure and outwardly to form supporting legs for said body, burners housed in said body, a cover member hingedly connected with one upper edge of the body and 85 adapted to be swung outwardly to horizontal position to form a supporting shelf or table and inwardly to close the said body portion, and a piece of attenuated spring metal bent to form an open grate hinged to 90 one edge of the body portion and pivoted to vertical position and horizontal position over the said burners, said hinged connection between the grid and the body comprising horizontally turned ends of the grid and sleeves 95 fixed to the body frame to receive them, the resilience of the spring metal of the grid being such that it may be flexed to remove said ends from their sleeves, but tending to hold them therein against normal stresses, including the stresses caused by using the grid as a handle to lift the stove means for connecting said legs in closed position and securing the cover formed thereby comprising a strap extending across one leg, said strap extending beyond the edges of the leg overlapping the edges of the body frame and having angular flanges engaging the exterior of said body frame.

11. In a device of the character described, 115 the combination of a hollow angular body frame open at top and bottom and having vertical sides and ends, sheet metal legs hinged to the lower part thereof at the ends and constructed and arranged to swing inwardly against the body frame to form a bottom closure and outwardly to form supporting legs for said body, burners housed in said body, a cover member hingedly connected with one upper edge of the body and adapted 120 to be swung outwardly to horizontal position to form a supporting shelf or table and inwardly to close the said body portion, a vertical folding shield on said table member extending along the outer edge thereof and 125 130

along the side edges thereof and over the body frame, said shield having its side portions foldable in horizontal plane on the rear portion and the said rear portion foldable therewith in vertical plane against the upper and inner surface of the table, the said connection comprising a sleeve member secured to the table, sleeves formed on both side and rear portions of the shield at their rear and side edges respectively and a pintle having an angular portion in said first-named sleeve and an upwardly extending portion extending through the said sleeve members of the shield portions, said sleeves on the shield portions being slidable on said upwardly extending pintle portion to remove the shield members therefrom.

14. A folding stove comprising a rigid rectangular body frame open at top and bottom, burners housed therein, legs hinged to the bottom end portions of the body, removable braces for securing said legs in open position, said legs forming a closure on one side of the body when closed, a table member hinged to the upper part of the body at one edge and forming a closure for one side of the body when in closed position, legs connected with said table member and movable to table supporting and housed positions, a grid hinged to said body and adapted to be swung to position over the burners and to upright position, a folding shield hinged to the table composed of hinged portions foldable against each other and against the table, all of said members being connected normally to form a unitary structure capable of being moved without becoming disconnected.

15. A folding stove comprising a rigid rectangular body frame open at its top and bottom, burners housed therein, legs hinged

to the bottom end portions of the body, removable braces for securing said legs in open position, said legs forming a closure on one side of the body when closed, a table member hinged to the upper part of the body at one edge and forming a closure for one side of the body when in closed position, legs connected with said table member and movable to table supporting and housed positions, a grid hinged to said body and adapted to be 45 swung to position over the burners and to upright position, a folding shield hinged to the table composed of hinged portions foldable against each other and against the table, all of said members being connected normally to be 50 moved without becoming disconnected, and said shield and grid being removable.

16. A folding stove comprising a rigid substantially rectangular body frame open 60 at its top and bottom, means for supporting burners therein above said open bottom, legs hinged to the lower end portions of the body and arranged to swing inwardly to close the bottom of said body and outwardly to open 65 and support the same, the construction and arrangement being such that when the legs are in open supporting position there is an unobstructed opening through which any fuel drippings or matters spilled from cooking utensils may fall to the ground or other supporting surface without lodging in the said body to cause fouling of the same or combustion exterior to the burners.

Witness our hands this 19th day of Aug., 70 1927, at the city of Milwaukee, in the county of Milwaukee, State of Wisconsin.

WALTER C. LINDEMANN.
ADOLPH W. BENSON.
